HAIR-CURLING DEVICE

Filed Nov. 3, 1949

UNITED STATES PATENT OFFICE

2,604,892

HAIR-CURLING DEVICE

Emma L. Keene, Spring Valley, Calif.

Application November 3, 1949, Serial No. 125,224

1 Claim. (Cl. 132—32)

1

This invention relates to a hair curling device and it is a particular object of the invention to provide a device of this kind which will enable a person to curl her own hair speedily and effectively.

Furthermore, it is an object of the invention to provide a device of this kind with means whereby the user may determine by finger touch the proper position of the device when in use.

The invention consists in the details of construction and in the combination and arrangement of the several parts of my improved hair curling device whereby certain advantages are attained, as will be hereinafter more fully set forth.

In order that my invention may be better understood, I will now proceed to describe the same with reference to the accompanying drawings, wherein:

Figure 1 is a view in perspective of a hair curling device constructed in accordance with an embodiment of the invention.

Figure 2 is a longitudinal sectional view taken substantially on the line 2—2 of Figure 1.

Figure 3 is a view in front end elevation of the device as illustrated in Figure 1;

Figure 4 is a fragmentary sectional view taken substantially on the line 4—4 of Figure 2;

Figure 5 is a view similar to Figure 3 but showing the fingers slightly separated; and

Figure 6 is a fragmentary transverse sectional view taken substantially on the line 6—6 of Figure 4.

As illustrated in the accompanying drawings the device comprises two members A and B of suitable material but preferably of plastic. The member A includes a forward portion 1 relatively broad and having an inner flat face 2 coplanar with an inner flat face 3 of a forwardly directed curling finger 4. This finger 4 is downwardly tapered from its inner end to its outer end and said finger 4 is also substantially semi-circular in cross section at all points therealong. The outer curved surface of the finger 4 is preferably roughened or knurled, as at 5 and said finger 4 at substantially the transverse center of the inner or flat face 6 thereof is provided therealong with a kerf 7 open at the outer end of the finger 4.

The inner flat face 2 of the forward portion 1 of the member A normally has close contact with the inner flat face 8 of the forward portion 9 of the member B and the inner flat face 3 of the finger 4 is normally in close contact with the inner face 10 of the finger 11 extending outwardly from the forward end of the portion 9 of the member.

2

The finger 11 is co-extensive in length with the finger 4 and tapered from its inner end to its outer end. The finger 11 is also substantially semi-circular in cross section from end to end and is provided throughout its length with a kerf 12 which registers with the kerf 7 of the finger 4. The outer curved surfaces of the finger 11 are also roughened or knurled, as at 14. The opposed walls of the kerfs of the fingers 4 and 11 are serrated and, together with the knurled outer surfaces of the fingers, function to grip strands of the hair to prevent slipping or bunching of the convolutions during the winding of the strands about the fingers.

15 The rear or inner end portions of the members A and B have their opposed inner flat faces 2 and 10 provided thereacross with the registering channels 15 and 16 respectively. The ends of the channel 16 are closed by the end walls 17 having 20 the outstanding semi-circular ears 18 which are received in the adjacent end portions of the channel 15 of the member A. Each of these channels 15 and 16 is also semi-circular in cross section from end to end and of a radius substantially the same as the radius of the ears.

25 The extremities of the channel 15 slightly inwardly of its ends are closed by the walls 19 having the outstanding ears 20 semi-circular in form and which extend within the channel 15 and in close contact with the inner faces of the end walls 17. The ears 18 of the end walls 17 are in close contact with the outer faces of the ears 20. (Figure 4.)

30 Disposed through the end walls 17 and 19 and the ears 18 and 20 is a headed pintle 21 whereby the members A and B are secured for relatively swinging movement. The free extremity of the pintle 21 after being applied has pressed on otherwise secured thereto a holding cap 22 which contacts from without with one of the end walls 17 and associated ear 18.

35 With the registering channels 15 and 16 is a coil spring 23 of requisite tension and encircling the pintle 21. One extremity of the spring 23 is engaged, as at 24, to the member A while the opposite extremity of the spring is engaged, as at 40 25, to the member B. This spring 23 maintains normally the opposed flat faces 2 and 8 of the members A and B respectively in close contact.

45 The member A has extending rearwardly therefrom a handle member 26 while the member B has extending rearwardly therefrom a handle member 27 herein disclosed as constituting a comb. The handle members, when the members A and B 50 are in their normal or closed positions, are so spaced apart that by suitable pressure thereon

by the hand of the operator grasping said handle members 26 and 27, the fingers 4 and 11 may be separated as desired.

The outer faces of the forward extremities of the members A and B immediately adjacent to the fingers 4 and 11 are provided with the raised portions 28 to enable the operator to locate by sense of finger touch the location of the kerfs 1 and 12 of the fingers 4 and 11 during a working operation which is particularly desirable when it is desired to insert or apply hair pins, clips or the like to fasten the curl of hair. It is believed obvious that in forming the curl, the ends of the hair lock will be clamped between the opposed faces of the fingers 4 and 11 after which the device will be rotated to wind the lock of hair around said fingers.

It is to be noted that the fingers 4 and 11 act as clamping jaws for the hair.

After the curl has been formed the fingers 4 and 11 will be separated sufficiently to release the lock whereupon the fingers will be withdrawn from within the curl.

From the foregoing description it is thought to be obvious that a hair curling device constructed in accordance with my invention is particularly well adapted for use by reason of the convenience and facility with which it may be assembled and used.

I claim:

In a hair curling device, a pair of elongated members formed to provide substantially spaced apart rear end portions, constituting handles, intermediate thickened portions having flat oppos-

ing surfaces and forwardly tapering front end portions of semi-cylindrical cross-section, the rear end portions of the thickened portions being inwardly recessed in the longitudinal direction, the side walls of the recess in one of the thickened portions being disposed in overlapping relation with respect to the side walls of the recess in the other thickened portion, a pivot pin passing through the said overlapping recess walls, and a coil spring associated with the pivot pin to hold the members normally parallel, the outer surfaces of the front end portions being knurled and these portions longitudinally halved by kerfs which extend forwardly from points slightly inward of the forward ends of the thickened portions.

EMMA L. KEENE.
